UNITED STATES PATENT OFFICE.

ANDERSON DAVIS ADAMS, OF GULFPORT, MISSISSIPPI.

STAKE-POCKET FOR LOGGING-CARS.

1,355,442.

Specification of Letters Patent. Patented Oct. 12, 1920.

Application filed August 16, 1919. Serial No. 317,990.

To all whom it may concern:

Be it known that I, ANDERSON DAVIS ADAMS, a citizen of the United States, and a resident of Gulfport, in the county of Harrison and State of Mississippi, have invented 5 certain new and useful Improvements in Stake-Pockets for Logging-Cars, of which the following is a specification.

My invention is an improvement in stake 10 pockets for logging cars, and the invention has for its object to provide a pocket especially adapted for receiving the stakes of logging cars wherein a channel-shaped pocket is provided, having a keeper permanently connected to one side of the pocket 15 and detachably connected with the other side, and normally held connected by releasable trip mechanism, capable of being operated simultaneously for all the stakes 20 of one side of a car, from the opposite side of the car.

In the drawings:—

Figure 1 is a perspective view of a portion 25 of a logging car provided with the improved pockets,

Fig. 2 is a transverse vertical section,

Fig. 3 is a front view of one of the pockets,

Fig. 4 is a side view showing the trip mechanism,

Fig. 5 is a top plan view of the keeper or shackle,

Fig. 6 is a front view of the said keeper or shackle,

Fig. 7 is a perspective view of the locking 35 eye-bolt,

Fig. 8 is a perspective view of the fixed eye for the keeper,

Fig. 9 is a perspective view of the latch bar,

Fig. 10 is a detail section showing the operating lever and its connections.

The present embodiment of the invention is shown in connection with the body 1 of a logging car, the said car being supported 45 by the usual wheels 2 on the axles 3. The car is provided with a series of pockets at each side, each of the said pockets being a channel plate consisting of a bottom wall 4 and side walls 5 and 6 respectively, and 50 at each side wall the pocket has extensions 7 and 8 lapping upon the car, and adapted to be secured thereto by bolts and nuts or in any other suitable manner.

Each pocket is an open channel as shown 55 and the stakes indicated at 9 are adapted to be held in the pocket by the shackle or

keeper 10 shown more particularly in Figs. 5 and 6. Each of these keepers has eyes 11 at its ends, and one of these eyes is connected with an eye 12 on a block 13, which 60 is arranged within a species of casing 14 on the outer side of the side wall 6 of the pocket.

Referring to Fig. 8 it will be seen that this block 13 has a threaded stem 15 which 65 passes through an opening at the bottom of the casing 14 through the extension 8, to the inner side of the car frame, where it is engaged by a nut 16 to hold the same in place. The other eye 11 of the keeper is 70 engaged with an eye 17 on one end of a bolt 18 which has a head 19 at the opposite end. This head is adapted to engage behind a locking lug 20 on the outer face of the side wall 5, and behind a catch 21 on a latch bar 22 which is pivoted at 23 to the 75 said side wall.

Referring to Figs. 4 and 9 it will be seen that the latch bar has a cylindrical head 24 encircling the pivotal connection 23, and 80 that the side wall 5 of the pocket has a lug 25 fitting below this head, so that the strain is taken off the pivotal connection, and brought directly on the pocket wall. In addition should the pivotal connection break, 85 the lug 25 which encircles the entire front of the cylindrical head 24 will serve as a bearing to prevent displacement of the bar and release of the bolt.

The latch bar is held in locking position, 90 that is, with its free end swung upward, by means of a holding bar 26 which is pivoted to the side wall 5 as indicated at 27. This holding bar has a cross head at its front end as shown in Fig. 4, one end of which engages a nose 28 on the latch bar, and the other, one end of a trip lever 29 pivoted at 30 below the holding bar. This trip lever is pivoted at its lower end, and the upper end engages the lower end of the cross head of the holding bar.

A link 31 is connected with the lever intermediate its ends, and this link extends through a slot 32 in the extension 7, and in the frame of the car to a connection with a 105 crank 33 on a shaft 34 journaled longitudinally of the car body at the adjacent side.

The shaft 34 is arranged adjacent to each side of the car body, and each shaft is connected to the links 31 of all of the adjacent 110 pockets. Referring especially to Fig. 2 it will be seen that the connection between the

links 31 and the cranks 33 is a lost motion connection, each link having a shackle or loop 35 at its inner end which engages the crank.

5 A handle 36 is secured to one or both ends of each shaft, and if desired the handles of the shafts may be connected by a link 37 and cause the shafts to move together, so that the keepers of all the pockets on either 10 side of the car may be simultaneously released.

Means is provided for preventing accidental movement of the shafts 34. The said means comprises a catch 38 on each shaft, 15 each catch being adapted to engage and hold to a pin 39 on the frame. In operation, to place the stakes, the bolts 18 of the keepers are engaged with the latch bars of the pockets, and the holding bar and the 20 trip lever are placed as shown in Fig. 4. The stake is now placed, and it will be obvious that there can be no release of the stakes until the lever 29 is swung inwardly at its upper end to release the holding bar.

25 As many pockets as may be desired may be placed at each side of the car, it being necessary only to equip the shafts 34 with the required number of cranks.

The operation is as follows:

30 To release the stakes on one side of the car, at the left of Fig. 2 for instance, the hook 38 at the right of the car is released, and the lever 36 at the said side is pulled outwardly. This movement pulls the lever 35 on the left of the car toward the center of the car, and likewise moves the crank on the left toward the center of the car, pulling the shackles 35, the links 31, and the trip levers 29 toward the center of the car, releasing all of the stakes on the left of the 40 car. However, the links 31 on the right of the car, that is, on the operator's side, are not affected, as the cranks travel in the space of the lost motion connection.

45 The principal feature of the hooks 38 is that when the operator raises the hook on

his side of the car, he can pull the levers 36 which will release the stakes at the opposite side of the car, but on account of the hooks 38 on the opposite side of the car, he cannot 50 release the stakes on his side, which would dump the logs onto him. The arrangement is thus a safety device.

I claim:—

1. In a car, the combination with the 55 body, of a series of stake pockets at each side of the car and each adapted to receive a stake, releasable means for holding each stake in its pocket, a link connected with each of said means and having a slot, a 60 shaft journaled at each side of the car and having crank portions engaged within the slots of all the links at the adjacent side of the car, radial arms connected for simultaneous movement and carried by said 65 shafts, the arrangement of said slots being to provide lost motion whereby when both shafts are rocked by movement of the arm at one side of the car, only the links and consequently the releasing means at the 70 other side of the car will be moved.

2. In a car, the combination with the 75 body, of a series of stake pockets at each side of the car, each pocket being adapted to receive a stake, releasable means for holding each stake in its pocket, a link connected with each of said means, a shaft journaled at each side of the car and connected with the links of the releasing means of all 80 of the pockets of the adjacent side to simultaneously release the same, each shaft having a radial arm for controlling the same, a connection between the arms for constraining them to move together, and a lost motion connection between each shaft and the 85 links at its side of the car for permitting said shaft to move with the shaft at the opposite side in its release of the series at the first named side without affecting the releasing means at the said opposite side, 90 and a safety catch for each arm.

ANDERSON DAVIS ADAMS.
